UNITED STATES PATENT OFFICE

155,030

DESIGN FOR A SUN VISOR

John Oswald, Detroit, Mich.

Application November 28, 1947, Serial No. 142,847

Term of patent 3½ years

(Cl. D14—6)

To all whom it may concern:

Be it known that I, John Oswald, a citizen of the United States, residing at Detroit, county of Wayne, and State of Michigan, have invented a new, original, and ornamental Design for a Sun Visor, of which the following is a specification, reference being had to the accompanying drawing, forming part thereof, in which:

Figure 1 is a perspective view showing my new sun visor design mounted on an automobile body.

Figure 2 is a front elevational view of the sun visor.

Figure 3 is a side elevational view of the sun visor.

Figure 4 is a cross sectional view taken on the line 4—4 of Figure 1.

Figure 5 is a plan view of the sun visor.

The dotted line showing in Figure 1 is for illustrative purposes only. The several drawing figures have been shaded to show contrasting appearance.

I claim:

The ornamental design for a sun visor, substantially as shown and described.

JOHN OSWALD.
